UNITED STATES PATENT OFFICE.

JAMES F. ILLINGWORTH, OF ITHACA, NEW YORK.

FILLING COMPOUND FOR TREE-CAVITIES.

1,217,181.

Specification of Letters Patent. Patented Feb. 27, 1917.

No Drawing.

Application filed September 5, 1912. Serial No. 718,670.

To all whom it may concern:

Be it known that I, JAMES F. ILLINGWORTH, a citizen of the United States, residing at Ithaca, in the county of Tompkins and State of New York, have invented new and useful Improvements in Filling Compounds for Tree-Cavities, of which the following is a specification.

My invention relates to a filling compound for tree cavities, and more particularly to such a compound as may be packed in a cavity or wound to close the same.

One object of the invention is to provide means whereby the cavity or wound of a tree may be so treated as to prevent further decay after filling, such as by contraction, or breaking away of the filling from the wood of the tree within the cavity, thereby exposing the wound to the action of the elements of the atmosphere and to water, such as rain.

In all of the compounds for the above purpose in use, as far as is known to me, contraction of the filling, or breaking away thereof from the wood within the cavity occurs, whereby the wound is exposed to the action of the elements of the atmosphere and rain may enter the wound, and cause further decay of the wood therein, which action it is sought to avoid by the use of the filling. It is also an object of my invention to provide a filling which will be free from the objection above noted and by such provision a compound that will form a close union, or effectively adhere to the wood, and a compound that will be water-proof, elastic, of light weight and inexpensive to manufacture.

Another object of my invention is to provide a filling of fluent material in the form of granules or small particles which may be slightly heated and tamped, or packed into the wound or cavity and preferably after first enlarging the cavity, cleaning and sterilizing the same, and applying to or painting the wood within the cavity with a suitable water-proofing agent in liquid state.

Another object of the invention is to provide the compound referred to of such composition as to enable the use of asphalt or asphaltum in its natural form or the oil thereof.

A further object of the invention is to provide a filling which may be applied in damp or rainy weather and also in cold weather, the latter being impossible where

cementitious material is used, the action of the filling not being affected by moisture or temperature.

Other objects and advantages of the invention will appear hereinafter from the description following:

In carrying out the invention, the wound or cavity of the tree is preferably first enlarged, cleaned or chipped out to remove decayed wood and is then sterilized. The cavity is preferably enlarged to such an extent or shape as to prevent the filling therein from falling therefrom should the filling sever or break from the wood within the cavity. Thereupon the wood within the cavity is preferably treated or painted with a suitable water-proofing compound which may be in the form of a liquid, and for which purpose a compound having pine tar, resin and asphalt as the ingredients in proper proportions has been found effective and satisfactory. After such treatment of the wound, my filling is inserted or applied, which filling is prepared and applied as follows:

A suitable quantity of asphalt or asphaltum, either in its natural form, or the oil, is mixed with a suitable filler, either organic or inorganic in nature, and such as saw-dust, sand, crushed rock, or the like, which has been found suitable both as to effectiveness and low cost. Said substances may be mixed in any suitable proportions desired. In use it has been found that seven parts of the filler to one part of the asphalt or asphaltum produces an efficient and satisfactory compound. In the preparation of the compound the filler is placed in the asphaltum while the latter is in a boiling state and the filler is preferably stirred or agitated in the hot or boiling asphaltum to insure that the cementitious material will coat each particle of the filler. The mixture is then allowed to cool and when cool assumes a granular form, or is in a mass of small particles and may be readily handled.

In this state the filling is used for insertion in the cavity or wound of the tree. But in applying the filler, it is preferably first slightly heated and in such state inserted or placed in the tree cavity or wound and then tamped or compressed into compact form to provide a solid filling upon setting or hardening.

The filling thus produced is water-proof, firmly adheres to the wood within the cavity

and being elastic, tends to hold itself firmly in position; thus obviating any danger of the filling being severed from the wood within the cavity and consequently the danger of 5 contraction of the filling, permitting rain and the elements to gain access to the wounded parts of the tree within the cavity, resulting in further decay. This danger which is avoided by my invention, often occurs 10 with the fillings now in use and before referred to and which fillings comprise in their composition, principally, concrete or cement.

As also set forth, the composition is one which will harden or set rapidly regardless 15 of weather conditions and hence is capable of application at all times.

Further, it will be evident that the composition thus formed is of such a nature that the inherently elastic qualities of the filler 20 are not materially interfered with by the use of the binder as the binder is not impregnated through the filler, but at the same time the coating of the particles of filling material protects the same against the absorption of moisture or against undue influence from external agencies.

The preferred embodiment of the composition has been set forth and described herein, but it will be understood that the steps taken in the mixing of the ingredients may be varied and that even the proportions could perhaps be changed, it however being essential that a relatively larger quantity of 25 filler material than of binder be employed,

and that other variations might be resorted to within the spirit and scope of the invention and the appended claims.

I claim:—

1. A filling compound for tree cavities consisting of an elastic and waterproof binder material and a proportionately large quantity of a body material inherently possessing expansive and contractile qualities similar to those of the wood of a tree and reduced to the form of particles, the binder being coated 40 on the particles of body material to leave the compound in the form of granules and small particles and to cause coherence of the particles while at the same time not materially effecting the expansive and contractile 45 qualities of the material of the body.

2. A filling compound for tree cavities consisting of substantially seven parts of a body material having inherent expansive and contractile qualities similar to those 50 of the wood of a living tree and the body material reduced to the form of particles, and substantially one part of an elastic and waterproof binder material mixed with the body material to coat the particles and to 55 leave the same in a granular form while at the same time waterproofing the particles and causing the same to cohere when placed and packed within the cavity of a tree.

JAMES F. ILLINGWORTH.
